METHOD OF MAKING BOBBED HAIR HOLDERS

Filed Sept. 24, 1925

FIG.1

FIG.2

FIG.3

Inventor
Haruko Saito
By *William Clinton* Attorney

UNITED STATES PATENT OFFICE.

HARUKO SAITO, OF TOKYO, JAPAN.

METHOD OF MAKING BOBBED-HAIR HOLDERS.

Application filed September 24, 1925. Serial No. 58,831.

This invention relates to an improvement in combs consisting in forming the same with a wire bent and twisted into teeth, and the object thereof is to obtain combs which efficiently keep the hair from going astray.

The accompanying figures show the combs of this invention, of which

Fig. 1 is a plan of a comb formed in a shape of a folding fan, and

Fig. 2 is a section of Fig. 1 on the line A—B.

Fig. 3 is a plan of the comb shown in Fig. 1 on which is twined another wire.

In the figures the same reference character refers to the same or corresponding part.

According to the present invention a comb is formed by bending a metal wire and twisting the bendings into teeth. To show more particularly how it is formed with reference to the accompanying figures, take a metal wire, bend it into **M** form with an equal space between two adjacent bendings (C) and repeat the process until the bent wire attains a desired length, leaving the first and last legs (a) somewhat longer than the bendings (C). Twist these bendings (C) into teeth, the twisted part being (d), bend the whole into a shape of a folding fan, and you will obtain a comb. Or it may

be left in a square form and in this latter case it is better to have the first and last legs much longer than the teeth.

In Fig. 3, another method of constructing a comb is shown. In this method a second wire (e) is entwined on the two outer legs and the base of the teeth, thus strengthening the comb.

In this invention a wire of any metal may be used, but it is better to form combs with steel wire. When a comb is formed with such wire, it is then tempered, and is made strong and elastic. Combs thus made, especially in the shape of a folding fan efficiently keep the hair from scattering, if it is stuck opening its teeth and legs a little.

Many modifications can be made in this invention without going out of its spirit.

I claim:

A method of making a comb consisting in forming it by bending a steel wire into **M** form with any desired space between two adjacent bendings, repeating the process until a desired length is reached, twisting all the bendings into teeth, leaving the two outer legs longer than the teeth, and tempering it.

In testimony whereof I affix my signature.

HARUKO SAITO.
